FOOTWEAR

Roy Maling, West Roxbury, Mass.

Application June 10, 1938, Serial No. 212,898

9 Claims. (Cl. 36—2.5)

This invention relates to improvements in footwear.

More particularly it provides improvements in heel structures for shoes and slippers, whereby heels may be more readily and practicably made in any of the wanted general types and styles, and with greater choice as to ultimate aesthetic effect, as compared with present practices.

It is among the objects of the invention to provide for the making of heels in any desired general type or style by assembling pre-formed and pre-finished heel units, so that finished surfaces of a plurality of superimposed units provide a composite finished surface of heel.

Another object is to provide for the practicable and economical finishing of edges of the heel units so that these edges can be combined to produce various aesthetic effects in a composite heel.

A further object is to provide for effective utilization of inexpensive matted fibre material which, in the unit construction of the invention, can provide a practicably stable, softly resilient heel.

It is, moreover, an important feature that my improved heels may be made and be combined with upper and outsole at costs which compare favorably with costs to produce competing shoes and slippers of equal grade but without the features and advantages of the invention.

The mentioned objects and results may be attained by forming suitably thick sheet-form heel units of any of various materials, which may be leather, rubber, wood, felt or any other fibrous or composition material having sufficient body and stability to serve in a heel structure as herein described. According to the invention a plurality of the units are assembled to form a heel, and each unit is pre-shaped to the desired cross-sectional shape of the heel at the region which will be occupied by the unit; and edges of each unit are pre-finished so that, when the units are superimposed one upon another, a composite finished surface of heel results, with prominent groove at each line of cleavage of units.

In a preferred form of the invention, the heel units are formed of inexpensive matted fibre material, and each unit has its edges, which would be exposed, finished and stabilized by a fabric binding which, besides covering the edges, extends inward a little over the margin of upper and under faces of the unit, and is there secured to the fibrous material. The binding of edges may be made to produce a slight or a prominent rounding of those edges to attain different effects when a plurality of the units are assembled to-

gether. And different colors or shades of binding on different units can be combined to attain various additional decorative effects.

The securing together of units may be by any well known device. In the case of matted fibrous material, the units may be stitched together conveniently and effectively, but I prefer to join them by cement or other adhesive which has a stabilizing effect upon the composite mass. However, in the case of high or medium high heels, a mechanical stiffener may extend across the cleavages of units.

It is intended that the patent shall cover, by suitable expression in the appended claims, whatever features of patentable novelty exist in the invention disclosed.

In the accompanying drawing:

Figure 1 is a side elevation of a shoe embodying features of the invention;

Figure 2 is a top plan of the shoe of Figure 1 with the upper and insole removed;

Figure 3 is an elevation in medial vertical section through the shoe of Figure 1;

Figure 4 is a perspective of the wedge heel and arch support of Figures 1-3; and

Figure 5 is an elevation showing the invention embodied in a different style of heel.

Referring to the drawing, the shoe upper 10 may be considered as representative of shoe and slipper uppers in general, inasmuch as the invention is not limited to any particular type or style of upper.

In Figures 1-4, the invention is portrayed as embodied in what conveniently may be termed a wedge type heel, whose use in shoes is characterized by extension of the heel under the arch of the foot, and by its requirement that the outsole shall be approximately flat from tip of toe to back of heel. Such a wedge type of heel, in its broader aspects, is not claimed as my invention, but only those structural features, as described herein, and as defined in the appended claims, which are applicable to the wedge type of heel as well as to other common types and styles.

According to the invention, the heel is constructed of heel units 12 each of which may be individually and preliminarily shaped to combine with other units in making any particular type or style of heel.

In the case of a wedge heel, as shown in Figures 1-4, the units extend forward to provide support at 13 for the arch of the foot, each unit having its forward portion gradually curving from top face to bottom face, with the upper 55

unit somewhat shorter than the under ones, so that a gradual, smooth curved support extends from top to bottom of a composite heel structure having two or more of the units superimposed one upon the other.

In a preferred form, the pre-formed heel units 12 are of matted fibre, or other suitably stable and durable cushioning material. I have found relatively highly compressed felt to be practicable and effectively usable in needed heights of heel. By making each unit of the order of one eighth to one half inch in thickness, and finishing its edges with a fabric or other binding 14, which serves also to stabilize the margin portions of a unit, a plurality of the units may be combined to produce a satisfactorily stable heel of a desired height, which may have a cushion effect in use superior to prior heel structures of which I have knowledge. The binding may be cemented to upper and under margins of the unit, or may be stitched through the unit, as indicated at 16. And it is an important feature that the binding of different units may have contrasting aspect as indicated in Figure 5.

25 If a material is used for the units 12 which can have its edges finished, without being bound, I prefer to round those edges slightly so that, when two or more units are assembled in superimposed relation, each line of cleavage of units 30 will be characterized by a prominent groove 18 extending around the heel.

When assembling the heel units novel and distinctive aesthetic as well as structural effects may be attained by a step arrangement of the units 35 as suggested in Figure 5. Obviously this step effect might be carried around the heel by forming the units successively smaller or larger. The same idea may be carried still further by alternating units of smaller and larger heel curvatures.

40 I claim as my invention:

45 1. A heel for footwear, comprising a plurality of sheet-form heel units individually pre-formed and individually finished by a binding strip secured to the margins of upper and under faces of each unit and covering the edge portions of the unit, said units being secured together in superimposed relation to provide a composite heel.

2. A heel for footwear as in claim 1, wherein the said sheet-form heel units are pre-formed of matted fibre material, and wherein edges of the respective units are individually covered with a

binding strip which extends inward over the margins of upper and under faces of the unit.

3. A heel for footwear as in claim 1, wherein the said sheet-form heel units are pre-formed of matted fibre material, and wherein edges of the respective units are individually covered with a binding strip which extends inward over the margins of upper and under faces of the unit, and wherein the binding strips of different units are of contrasting aspect. 10

4. In a shoe or the like, a plurality of sheet-form heel units individually pre-formed and individually finished along an edge by a binding strip covering said edge and secured to the margins of upper and under faces of the unit; said units being secured together in superimposed relation to constitute a composite heel body for the shoe, and extending forward as an arch support at the shank of the shoe. 15

5. A resilient heel for shoes and the like, comprising a plurality of sheet-form matted fibre heel units individually pre-formed and individually stabilized by a binding strip secured to the margins of upper and under faces of the unit and covering the edge portions of the unit at the surface of the composite heel; said units being further stabilized by being cemented together in superimposed relation. 20 25

6. A heel for footwear, comprising a plurality of sheet-form heel units individually pre-formed of resilient material and individually finished along an edge by a binding strip covering said edge and secured to the margins of upper and under faces of the unit; said units being secured together in superimposed relation to constitute a composite heel for a shoe, and having a portion extending forward for constituting an arch support at the shank of a shoe. 30 35

7. A heel for footwear as in claim 6, wherein the said sheet-form heel units are pre-formed of mat- 40
ted fibre material, and wherein the said portion extending forward is approximately wedge-shaped, for fitting the shank of a shoe.

8. A heel for footwear as in claim 6, wherein the said sheet-form heel units are of different lengths progressively through the height of the composite heel, with the longer unit adjacent to the tread element of the heel. 45

9. A heel for footwear as in claim 6, wherein the said sheet-form heel units are pre-formed of 50 resilient material.

ROY MALING.
